HOLDER FOR TOOTHPICKS OR SIMILAR ARTICLES

Charles B. Overbaugh, Denver, Colo.

Application May 10, 1952, Serial No. 19,676

Term of patent 14 years

(Cl. D44—24)

To all whom it may concern:

Be it known that I, Charles B. Overbaugh, a citizen of the United States, residing at the city and county of Denver, State of Colorado, have invented a new, original, and ornamental Design for a Holder for Toothpicks or Similar Articles, of which the following is a specification, reference being had to the accompanying drawing, forming a part hereof.

Fig. 1 is a side elevational view of a holder for toothpicks or similar articles, showing my new design.

Fig. 2 is a top plan view of the same.

Fig. 3 is an isometric view of the same on a somewhat reduced scale.

I claim:

The ornamental design for a holder for toothpicks or similar articles, as shown.

CHARLES B. OVERBAUGH.
